SEAL FOR FLOATING TANK ROOFS

John H. Wiggins, Tulsa, Okla.

Application April 12, 1934, Serial No. 720,158

6 Claims. (Cl. 220—26)

This invention relates to seals for floating tank roofs, my present application being a continuation in part of my pending application for Patent Serial No. 436,217, filed March 15, 1930.

5 One object of my present invention is to reduce the cost, reduce the number of parts and simplify the fabrication and installation of the so-called Wiggins type seal for floating tank roofs.

10 Another object is to provide a novel hanger structure or shoe supporting means for floating tank roof seals, that is inexpensive, reliable in operation, and of such design that it can be fabricated at a factory and then shipped as a unit

15 to the field and mounted quickly and accurately on the floating tank roof on which it is used.

I have herein illustrated my invention embodied in a seal for a floating tank roof of the pontoon type, but I wish it to be understood that my invention is applicable to and capable of use with

20 floating tank roofs of the so-called "pan" type.

Figure 1 of the drawing is a fragmentary top plan view of a floating tank roof equipped with a seal constructed in accordance with my present invention.

Figure 2 is an enlarged fragmentary vertical sectional view, taken on the line 2—2 of Figure 1, looking in the direction indicated by the arrows.

Figure 3 is a vertical sectional view, taken on the line 3—3 of Figure 2.

Figure 4 is a horizontal sectional view, taken on the line 4—4 of Figure 2, illustrating one of the vertically-disposed fabric elements used to close the gap between adjacent shoe members;

35 and

Figure 5 is a fragmentary perspective view, illustrating the means that I prefer to use for connecting the fabric elements to the parts of the structure with which they co-act.

The Wiggins floating tank roof seal that is now in extensive use, comprises a vertically-disposed, annular metal shoe of considerable height, arranged substantially parallel to and in sliding engagement with the side wall of the tank, and joined to the floating tank roof usually by a fabric element that serves as a closure for the space between said shoe and floating roof. The common practice for many years has been to construct said annular shoe from a relatively large number of vertically-disposed shoe members (usually about 3 ft. in length) made of stiff or heavy flanged metal plates, joined together by vertically-disposed fabric elements that close the gaps between adjacent shoe members. On account of the relatively large number of shoe mem-

bers and fabric connecting elements required for the seal (usually in excess of 100 each for a tank of 50,000 barrel capacity) the cost of fabricating and installing the annular shoe is an item of considerable importance in the total cost of a Wiggins tank roof seal, as the shoe members are individually mounted on hangers and a vertically-disposed fabric element has to be arranged between and connected by two gas-tight joints to the two shoe members at the opposite sides of the gap which the fabric element closes. Moreover, as the shoe members were made of relatively heavy or thick metal plates whose upper and lower edge portions were flanged or bent inwardly, it was impossible for the individual shoe members to flex circumferentially intermediate their ends, or flex in such a way as to accurately conform to the curvature of the side wall of the tank.

The seal herein described which constitutes my present invention, departs radically from the previous commercial practice in constructing Wiggins tank roof seals, in that it comprises an annular shoe constructed in such a way as to comprise a relatively small number of segmental sections or shoe members, each of which is substantially arc-shaped and capable of flexing circumferentially intermediate its ends, sufficiently to conform to or adapt itself to the curvature of the side wall of the tank, even a side wall that is slightly out of round or not of truly cylindrical shape. This highly desirable result is attained by substantially increasing the length of the shoe members or segmental portions of the shoe and making them in such a way that the beveled or inwardly bent upper and lower edge portions of same, used to guide the shoe over protuberances or irregularities on the inner face of the side wall of the tank, will not retard or interfere with the circumferential flexing of said shoe members. Due to the fact that the inwardly directed means on the upper and lower edge portions of the shoe members are constructed in such a way that the shoe members have only a single curvature, said shoe members may be formed from metal plates that are either of conventional thickness or lighter or thinner than has heretofore been the custom.

In the accompanying drawing which illustrates the preferred form of my invention, the reference character A designates as an entirely floating tank roof which may either be of the pan type, or of the pontoon type, the roof being herein illustrated as provided at its peripheral edge with a pontoon 1. At the peripheral edge

of the roof A is a seal that comprises an an-
5 basic principles or distinguishing characteristics
basic principles or distinguishing characteristics
of the Wiggins tank roof seal, i. e., it is of con-
siderable height or depth and has a substantial-
10 ly vertically-disposed portion of considerable
area arranged in parallel or substantially par-
allel relation to the side wall 2 of the tank. Said
annular shoe is made of relatively thin or light
15 gage metal plates, and in a seal for large-sized
tanks the annular shoe will comprise only a small
fraction of the number of shoe members of a
conventional Wiggins tank roof seal. Each shoe
20 member is provided with a guiding means that
insures the shoe member sliding freely over pro-
jections, protuberances or irregularities on the
inner face of the side wall of the tank, but said
guiding means is so constructed that it will not
25 retard or prevent the shoe member from flexing
circumferentially intermediate its ends, suffi-
ciently to conform with considerable accuracy to
the curvature or shape of the side wall of the
30 tank.

Preferably, said annular shoe is made up of
25 a plurality of relatively long, circumferentially
flexible shoe members B, each of which comprises
a vertically-disposed portion of arc shape in hori-
zontal section, that is disposed in parallel or
substantially parallel relation to the side wall of
30 the tank. The number of said shoe members
will vary according to the diameter of the tank,
but said shoe members will be made of such
length that each of same will have sufficient in-
herent flexibility (circumferentially) to cause it
35 to follow the curvature or outline of the tank
side wall. On a large tank of great storage ca-
pacity, say, for example, a tank having a di-
ameter of approximately 100 ft., each shoe mem-
ber B will be approximately 30 ft. long, or, in
40 other words, about ten times as long as the shoe
members heretofore used in Wiggins tank shoe
seals. The gap or gaps formed by the space or
spaces between the ends of the shoe members B
45 are closed by vertically-disposed fabric elements
3 which are attached to the ends of the shoe
members, preferably in a manner hereinafter
described. While I have stated that the shoe
members B are usually made about 30 ft. in
50 length, this is not essential. The point that I
desire to emphasize is that my present invention
makes it practicable to use any length of shoe
member that can be handled conveniently in the
operation of erecting or installing the seal. In
55 fact, on small-sized tanks, the annular shoe of
the seal may consist of a substantially continu-
ous, circumferentially flexible structure provided
with a single gap in which a vertically-disposed
fabric element is arranged to seal or close said
60 gap. In order to guide the shoe members B
over the inner face of the side wall of the tank
and prevent said shoe members from catching
on projections or protuberances on said side wall,
I provide the upper and lower end portions of
65 said shoe members with beveled or inwardly bent
portions 4, as shown in Figure 5. Unless means
were provided to overcome the stiffening effect
produced by said inwardly bent portions 4, the
shoe members would not flex circumferentially
70 intermediate their ends, as previously described.
Accordingly, I provide the flanged or inwardly
bent portions 4 of each shoe member B with a
plurality of vertically-disposed slits, notches or
saw kerfs 4^a, as shown in Figure 5, that do not
75 interfere with the proper functioning of said
guiding portions 4, but which effectively prevent

said portions 4 from interfering with the circum-
ferential flexing of the shoe members, said slits
or slots 4^a extending inwardly to the points where
the portions 4 are bent inwardly.

The shoe members B are sustained by hanger
structures of novel construction, designed so that
each hanger structure may, if desired, be built
and assembled in a factory and then taken as a
unit to the field and mounted quickly and accu-
rately on the floating roof on which it is used.
10 Said hanger structures are so made and are
mounted on the floating roof A and combined
with the shoe members B in such a way, that
said shoe members will be maintained in parallel
relationship with the side wall 2 of the tank, and
15 movement of said shoe members inwardly, to-
wards the floating roof, will be resisted by a
resilient means which tends to hold the floating
roof and the annular shoe in approximately con-
centric relationship. The specific number of
20 hanger structures that is employed for each
shoe member may vary, but I prefer to space
the hanger structures about 3 ft. apart so as
to provide an adequate supporting means for
the annular shoe that contacts the vertical side
25 wall of the tank. In the form of my invention
herein illustrated each of the hanger structures
just referred to comprises a substantially elbow-
shaped lever or hanger C pivotally mounted at
30 5 on a pair of vertically-disposed uprights 6 in
such a way that one arm 7 of said hanger will
project downwardly and outwardly towards the
side wall 2 of the tank, and thus permit the lower
end of said arm to be attached to its shoe member
35 B by a pivot or pintle pin 8 which is located at a
point considerably below and on the outside of
the pivot 5 of the hanger. As shown in Figure 3,
the pivot or pintle pin 8 which joins the shoe
member to the lower end of the arm 7 of the
40 hanger is located near enough to the upper edge
of the shoe member to assure the shoe member
naturally assuming a substantially vertical or
upright position with the lower end of same en-
gaging the side wall of the tank. The other arm
45 7^a of the hanger projects inwardly in a substan-
tially radial direction, towards the center of the
floating roof A, and a spring 9 is attached to
the inner end of said arm 7^a in such a manner
that when the downwardly-projecting arm 7 of
50 said hanger swings outwardly towards the side
wall of the tank, the tension of said spring 9 will
be decreased, and when said downwardly-pro-
jecting arm 7 swings inwardly, towards the float-
ing roof, the tension of said spring 9 will be
55 increased. Accordingly, in a floating tank roof
seal equipped with hanger structures of the de-
sign above described, there will be a natural
tendency for the annular shoe and the floating
60 roof to remain in substantially concentric rela-
tionship, with the shoe members B in a vertical
position in snug engagement with the side wall
of the tank. No stops or abutment devices are
65 required to limit the outward movement of the
shoe members, i. e., movement away from the
floating roof. Instead, the springs 9 are so ar-
ranged that the tension of same is increased by
70 movement of the shoe members inwardly to-
wards the floating roof, and hence, such inward
movement of the shoe members causes the
springs 9 to function to restore the approximately
75 concentric relationship between the shoe mem-
bers and the floating roof, and hold the roof
properly centered with relation to the side wall
of the tank.

The pair of uprights 6 on which each hanger
75

C is pivotally mounted are constructed so that the upper ends of said uprights embrace the hanger and are held together by a bolt or other suitable fastening means 5 that constitutes the 5 pivot of the hanger. The lower ends of said uprights 6 are spread or flared slightly, as shown in Figure 2, and if desired, they may be combined with inclined braces 10. Said uprights or supports 6 and the inclined braces 10 that cooperate with same, are preferably welded to the peripheral portion of the floating roof, as, for example, to the top side of the pontoon 1, but said uprights may be connected in any other suitable way to the floating roof. Whatever 10 method is employed to attach the uprights 6 to the floating roof, one decided advantage of the hanger structure above described is that it may be constructed as a unit in a factory and then shipped in an assembled state to the point where 15 it is to be used and then mounted quickly and accurately on the floating roof. As shown in Figure 3, the lower end of the spring 9 of each hanger structure is attached to one of the uprights 6 of the structure.

25 A substantially annular-shaped fabric element 3^a is attached to the peripheral edge of the floating roof and to the annular shoe formed by the shoe members B, so as to form a closure for the space between the floating roof and the side 30 wall of the tank. The connecting means used to join said fabric element 3^a to the metallic parts with which it co-acts, preferably comprises substantially horizontally-disposed metal clamping rods or bars 11 and 11^a, superimposed upon or 35 arranged in engagement with the top side of said fabric element 3^a adjacent the inner and outer edges of same, a plurality of substantially hook-shaped devices 12 and 12^a on the top side of the pontoon 1 and on the inner sides of the shoe 40 members B, disposed in overlapping relation with said rods 11 and 11^a and retaining wedges 13 and 13^a driven between said rods and hook-shaped devices, as shown clearly in Figure 5, the hook-shaped devices 12 and 12^a being welded or connected in any other suitable way to pontoon 1 and to the shoe members B. The means 45 that is used to connect the vertically-disposed fabric elements 3 to the ends of the shoe members B is of substantially the same construction and comprises vertically-disposed clamping rods 50 or bars 11^b, arranged in engagement with said fabric elements 3, so as to clamp each fabric element 3 securely to the pair of shoe members B with which it co-acts, horizontally-disposed, 55 hook-shaped devices 12^b on the shoe members that overhang or lap over said clamping rods, and wedges 13^b driven between said clamping rods and hook-shaped devices, so as to securely retain the clamping rods in position. The annular fabric element 3^a is connected to the upper 60 ends of the vertically-disposed fabric elements 3 in a conventional manner, so as to produce gas-tight joints between said parts, and some suitable adhesive or sealing substance is also

preferably applied to the surfaces of the metal parts to which the fabric elements are clamped.

Having thus described my invention, what I claim as new and desire to secure by Letters Patent is:

1. The combination of a floating tank roof, an annular seal shoe surrounding said roof and adapted to contact the side wall of the tank, and hanger structures on said roof that sustain said shoe, each of said hanger structures consisting of a self-contained or assembled unit made up of a vertically-disposed standard arranged entirely within the marginal limits of the floating roof, a rockable hanger pivotally connected to the upper end of said standard at a point within the peripheral edge of said floating roof, and a spring combined with said hanger and support for maintaining the shoe in substantially concentric relation with the roof.

2. The combination of a floating tank roof, an annular seal shoe surrounding said roof and adapted to contact the side wall of the tank, and hanger structures on said roof that sustain said shoe, each of said hanger structures comprising a pair of vertically-disposed standards adapted to be mounted on and connected to the roof at a point within the marginal edge of said roof, a rockable hanger embraced by said supports and pivotally connected to the upper ends of same, and a spring attached to said hanger and disposed so as to resist movement of the shoe, inwardly towards the roof.

3. A seal for floating tank roofs, comprising an annular metal shoe, arranged vertically in substantially parallel relationship with the inner face of the side wall of the tank, said shoe comprising segments which are of substantial length and of single curvature, to permit said segments to flex intermediate their ends so as to follow the curvature of the side wall of the tank.

4. A seal for floating tank roofs of the kind described in claim 3, in which the segments of the shoe have spaced, inwardly directed means on their upper and lower edge portions, for guiding said segments over projections or protuberances on the side wall of the tank.

5. A seal for floating tank roofs of the kind described in claim 3, equipped with flexible seals for the joints between the vertical edges of the segments of the shoe.

6. The combination of a tank, a floating roof for said tank, and a seal for said floating roof, said seal comprising an annular metal shoe, arranged vertically in substantially parallel relationship with the inner face of the side wall of the tank, the said shoe comprising segments of substantial length and of single curvature to permit said segments to flex intermediate their ends to follow the curvature of the side wall of the tank, and a flexible sealing means between the inner face of said shoe and the outer edge of the floating roof.

JOHN H. WIGGINS.

CERTIFICATE OF CORRECTION.

Patent No. 2,082,194.

June 1, 1937.

JOHN H. WIGGINS.

It is hereby certified that error appears in the printed specification of the above numbered patent requiring correction as follows: Page 2, first column, line 1-2, strike out the syllable and words "an- basic principles or distinguishing characteristics" and insert instead annular metal shoe which embodies one of the; and that the said Letters Patent should be read with this correction therein that the same may conform to the record of the case in the Patent Office.

Signed and sealed this 20th day of July, A. D. 1937.

Henry Van Arsdale
